[57] CLAIM

The ornamental design for an exterior vehicle visor or similar article, as shown and described.

DESCRIPTION

FIG. 1 is a front elevation view of an exterior vehicle visor or similar article showing my new design;

FIG. 2 is a top plan view thereof;

FIG. 3 is a bottom plan view thereof, but forms no portion of the claimed design of the present invention and is illustrated merely for purposes of compliance with 35 U.S.C. Section 112 (1st paragraph);

FIG. 4 is a left side elevation view thereof; and

FIG. 5 is a right side elevation view thereof.

*FIG. 2**FIG. 1**FIG. 3**FIG. 4**FIG. 5*
